UNITED STATES PATENT OFFICE.

GEORGE H. DAVIS, OF PORTLAND, MAINE, ASSIGNOR TO THE CURTAIN SUPPLY COMPANY, OF CHICAGO, ILLINOIS, A CORPORATION OF NEW JERSEY.

WINDOW-SHADE-HOLDING DEVICE.

No. 893,458.

Specification of Letters Patent.

Patented July 14, 1908.

Application filed March 28, 1905. Serial No. 252,510.

To all whom it may concern:

Be it known that I, GEORGE H. DAVIS, a citizen of the United States of America, and a resident of Portland, Cumberland county, 5 State of Maine, have invented certain new and useful Improvements in Window-Shade-Holding Devices, of which the following is a specification.

This invention relates to improvements in 10 curtain or shade holding fixtures, and has for its object the provision of a device designed primarily for use in connection with a spring actuated roller and adapted to engage the runway of a window frame to hold a shade in 15 desired positions of adjustment, said device including an elongated head, a friction surface or surfaces carried thereby for engagement with the base of said runway, and anti-friction surfaces arranged to contact with the 20 side or confining walls of the groove, the purpose of these anti-friction surfaces being to facilitate a free and easy manipulation of the fixture by overcoming the objections to existing devices wherein an elongated carrying 25 head or shoe for the friction surface, presenting relatively extensive side surfaces, enters the guide-way or groove in the frame or casing, and in its vertical sliding movement under the pressure of the hand is oftentimes 30 forced into frictional contact with said side or confining walls of the groove thereby correspondingly retarding the shifting of the head in said groove, a fixture of this last 35 mentioned type being illustrated in the Forsyth patent No. 559,446.

Several convenient embodiments of the invention disclosing the underlying principle of the same are illustrated in the accompanying drawings, and upon an inspection thereof in 40 connection with the detailed description hereinafter given, it will be apparent that the advantages inherent in an elongated head or shoe are preserved in addition to the accomplishment of the ends desired to be attained 45 by the present improvements. These particular embodiments also possess novel details of construction and arrangement as will be presently defined.

In the drawings, Figure 1, is a front elevation of a portion of a window frame or casing showing the usual constantly acting spring roller mounted at the upper portion thereof, the curtain or shade secured thereto, and one

form of holding fixture carried by the bottom of the curtain, parts being broken away to 55 disclose the interior portions of said fixture; Fig. 2, is an end elevation of the fixture just referred to, the side or confining walls of the guide-way or groove being shown in section; Fig. 3, is an elevational-sectional view of one 60 end of another form of fixture; and Fig. 4, is an end view of the same.

Referring more specifically to the drawings in the respective series of views of which corresponding reference characters refer to the 65 same parts, and now with reference more particularly to Figs. 1 and 2, A designates the frame or casing of an ordinary window, and B inwardly facing guide-ways or grooves formed therein. C is a constantly acting 70 spring roller common in this art, mounted at the upper end of the frame A; D the curtain or shade secured to said roller adapted to wind upon or be unwound from the same according to the adjustment of the shade de- 75 sired, and E is a tube or housing carried by the bottom of the shade and constituting a part of the holding fixture designed to resist the winding of the shade upon the spring roller whereby to maintain the former in ad- 80 justed positions. Secured to the ends of the tube E are hollow heads F having a threaded engagement f to permit of the proper adjust- 85 ment of the same relative to the bases b of the grooves B. Adapted to be reciprocated 90 within the hollow heads F and the tube E are oppositely disposed rods G each branched at its outer end to provide vertical arms g, these 95 arms in turn being off-set to provide exten- sions g' arranged parallel with the longitudi- 100 nal axis of the rod, as clearly indicated in Fig. 1. Upon the extremities of the exten- sions g' are friction shoes or surfaces H de- 105 signed to bear against the base b of the guide groove B, said shoes being of any desired sub- stance such as rubber or metal, preferably the latter, and rounded as shown to permit the fixture to rock thereon to a limited ex- tent when the same is canted so as to facilitate the self-righting of the fixture. Any 100 suitable instrumentalities may be afforded for creating the desired holding pressure be- 105 tween the surface of the shoes and the base of the groove, for instance a spring I carried upon the rod G, at one end engaging a pro- jection i on the rod and at its opposite end

bearing against a fixed abutment i' on the interior of the tube E. The tendency of the spring is of course to normally thrust the shoes H into contact with the base of the 5 grooves. Although the fixture may be employed without the provision of retracting means, I have shown the inner ends of the rods G as formed with pendants or pinch handles J depending through a slot j in the 10 bottom of the tube E.

Surrounding the friction shoes H I provide anti-friction devices K, the same being in the nature of hollow rollers flanged at one end as at k and carrying suitable bearings 15 k' sleeved for rotary movement upon the extensions g' of the arms g , said rollers being of a size to engage and run along either of the side or confining walls b' of the groove B should the same be thrown into contact 20 therewith by the lateral movement of the fixture under the pressure of the hand in adjusting the shoe, so as to prevent any frictional resistance to the raising and lowering of the fixture within the guide ways as is obvious. 25

In Figs. 3 and 4, E' represents a stick corresponding to the tube E in the first two figures, said stick being bored at its ends for the reception of short rods G' carried by the 30 heads F', said rods being backed by springs I' and restricted in their movements by pins L working in short slots l in the stick, said slots opening to the bores at the ends of the stick. At the ends of the head F' are stub 35 pintles m carrying friction shoes or surfaces M adapted to engage the base n of the guide-way or groove N, and upon these pintles and intermediate the friction shoes or surfaces M and the head F' are rollers K' adapted to engage the side or confining walls n' of the 40 groove N.

Having thus described the invention what is claimed as new and desired to be secured by Letters Patent is:—

45 1. In a curtain holding device, the combination with the curtain stick and a spring roller curtain, of a rod or spindle longitudinally movable in said curtain stick, a friction tip on the outer end of said rod or spindle, a spring for forcing the same outward, means for withdrawing the same, and a rotatable sleeve surrounding said tip and journaled on the end of said rod to form an anti-friction roll.

55 2. A curtain holding device having an elongated head, separate friction devices, instrumentalities for mounting the same one adjacent to each end of the head for engagement with the base of a guide groove, and for 60 releasing the friction devices, and an anti-friction device connected to move with the head and contact with the side or confining wall of said groove, when said friction devices are released.

3. A curtain holding device having an elongated head, separate friction shoes, means for mounting the same to move with the head one adjacent to each end of the head for engagement with the base of a guide groove, and anti-friction rollers mounted 70 upon said mentioned means adapted to contact with the side or confining walls of said guide groove.

4. A curtain stick, and a friction device for engagement with the base of a guide groove, 75 a rotatable sleeve loosely surrounding said device and arranged to contact with the side or confining wall of the groove, and means whereby both of said devices are operatively connected with the stick to move therewith. 80

5. In a curtain fixture, a head, a rod extending beyond the head, a frictional device secured to the end of the rod and arranged to engage the base of the groove, and an anti-friction device journaled on the rod and arranged to engage the side of the groove. 85

6. In a curtain fixture, a head, a rod extending beyond the head, a friction device fixed to the end of the rod arranged to engage the bottom of the groove, and an anti-friction device for engaging the side of the groove comprising a substantially cup-shaped member journaled on the rod and surrounding the friction device. 90

7. In a curtain fixture, the combination 95 with a curtain, of a holding device therefor, including a friction shoe, a sleeve so mounted as to extend over the shoe and rotatable independently thereof, and means for mounting the shoe and sleeve at the end of the stick, 100 whereby the shoe will engage the base of the groove and the sleeve the side of the groove to form an anti-friction roller.

8. A holding fixture for curtains having instrumentalities for frictionally engaging 105 the base of a guide groove and for preventing frictional contact of the fixture with the side or confining walls of said groove, and means for operatively connecting said instrumentalities together and to the curtain, including a single supporting rod for the instrumentalities. 110

9. In a curtain fixture, the combination with a curtain, of a holding device therefor including a friction shoe fixed against rotary movement and arranged to engage the base 115 of the window frame groove, and a rotatable device adapted to engage the side or confining wall of the groove, and means common to the shoe and device for operatively connecting the shoe and device to the curtain. 120

10. In a curtain fixture, a head, a rod in the head, a friction device secured to the end of the rod and arranged to engage the base of the groove, and an anti-friction device journaled on the rod and arranged to engage 125 the side of the groove.

11. In a curtain fixture the combination of a head, a friction device carried by the head

fixed against rotary movement, and adapted to engage the base of a window frame groove and an antifriction roller also carried by the head arranged to engage the side of the confining wall or groove thereby affording an antifriction bearing for the head when released by the frictional device.

Signed at Portland Maine this 23d day of March 1905.

GEORGE H. DAVIS.
